UNITED STATES PATENT OFFICE.

HYMAN ELI GOLDBERG, OF CHICAGO, ILLINOIS, ASSIGNOR TO GOLDBERG CALCULATING MACHINE COMPANY, A CORPORATION OF ILLINOIS.

CALCULATING-MACHINE.

No. 893,726.

Specification of Letters Patent.

Patented July 21, 1908.

Application filed October 22, 1906. Serial No. 339,984.

To all whom it may concern:

Be it known that I, HYMAN ELI GOLDBERG, a citizen of the United States, residing at Chicago, in the county of Cook and State of Illinois, have invented a certain new and useful Improvement in Calculating-Machines, of which the following is a specification.

My invention relates to calculating machines including typewriter attachments and 10 the object of the invention is to provide a novel and useful form of automatic mechanism which may be positioned before the beginning of any particular operation or problem, for determining whether or not the totalizer shall be operative or non operative in 15 any particular column and if operative, in which direction, addition or subtraction.

The machine here shown is similar in many respects to the ones shown and claimed in 20 four previously filed patent applications for calculating machines; to wit:

275,780, filed August 25, 1905;
292,932, filed December 22, 1905;
313,070, filed April 21, 1906;
25 326,081, filed July 13, 1906.

In the present machine there is a laterally fixed differential mechanism and a traveling totalizer or columeter as in applications 30 above referred to. The novelty in the present case resides in the mechanism for transmitting motion from the differential mechanism to the totalizer and in the means whereby this transmitting mechanism is controlled.

Referring to the accompanying drawings which form a part of this specification: Figure 1 is a general front view of a typewriter having attached thereto calculating mechanism embodying the invention. Fig. 2 is a 40 plan view intended chiefly to show the transmitting mechanism and controlling means therefor. Fig. 3 is a front elevation of the parts shown in Fig. 2. Figs. 4 and 5 are sectional views taken respectively on lines 4—4 and 5—5, Fig. 2. Figs. 6, 7 and 8 are views showing a controlling pin and illustrating the three different positions which it may occupy. Fig. 9 is a fragmentary view showing 45 the controlling cam or track on the totalizer casing. Figs. 10 to 17 inclusive show the construction of the totalizer. Fig. 10 is a front assembly view of the totalizer partly in section showing the relation of the different

parts. Fig. 11 is similar to Fig. 10 except 55 that it shows the different component parts spread somewhat to illustrate their relationship. Fig. 12 is a sectional view of the intermediate wheel located farthest to the right in the totalizer. Fig. 13 is a sectional view 60 taken on line 13—13, Fig. 10. Figs. 14 to 17 inclusive are side views of component parts of the totalizer.

Similar numerals refer to similar parts throughout the several views.

The typewriter shown is of a well known pattern and has a stationary framework 1 and a traveling carriage 2 and keys 3. Said keys in addition to operating the printing mechanism (which is not illustrated as it 70 forms no part of the present invention) operate the differential mechanism 4 which may be of any suitable construction, for example as shown in Patent No. 782,554, granted to me March 7, 1904. By means of the differential mechanism movement is imparted to the shaft 5 in proportion to the value of the key depressed. Said shaft is permanently 75 gear connected to the gears 6 and both the shafts and gears 6 may be considered as being a portion of the differential mechanism.

The construction of the totalizer is not an essential feature of this invention. If a machine is desired in which the operator is to have the choice only as to whether the machine 85 shall operate or not operate the totalizer need not be reversible but if a machine is desired which shall be susceptible of the full benefit of this invention and the operator is to have the choice as to whether the machine 90 shall add, subtract or not operate then the totalizer must be reversible. The totalizer here shown is reversible and its construction is identical with the one for which a patent was granted to me February 15, 1905, No. 95 782,605. It will be understood however, that other forms of totalizers may be employed without departing from the spirit of the invention. The totalizer will be herein-after described but for the present it is sufficient to say that it contains a set of receiving wheels 33 which operate the totalizer parts and are adapted to mesh with the setting wheels 8 as the totalizer travels past them. The totalizers travel in unison with the typewriter carriage and the motion of the carriage is transmitted to the totalizers through any suitable agency, for example, the arm 9 100 105

engaging the slide 10 which travels upon the guide bar 11. Slide 10 has a rectangular bar 12 rigidly secured thereto upon which one or more totalizers are rigidly fastened. The 5 totalizers are preferably adjustable lengthwise of bar 12, but when once set, the totalizers move with the bar in a fixed path so that their controlling cams 25 may operate a certain controlling device hereinafter described.

10 The setting wheels 8 above mentioned are mounted upon shaft 13. To obtain the fullest scope of the invention they should be independently rotatable especially if a plurality of totalizers is employed, but practical results may be obtained with some or all of said setting wheels rigidly secured to shaft 13 if said shaft is rotatable. In the preferred construction shown, in which the wheels are 15 independently rotatable they are loose upon the shaft and held in proper positions laterally by means of the spacing collars 8^a.

20 From the description thus far it will be evident that when a figure key is depressed 25 the typewriter carriage will be shifted and will bring the receiving wheels 33 into mesh *seriatim* with any given setting wheel. This feature is common to previous machines. I 30 will now describe the transmitting and controlling mechanisms which embody the novel features of the present machine.

25 *Transmitting mechanism.*—Upon a platform 14 attached to any suitable portion of the framework 1 is slidingly mounted a plate 15. This plate is adapted to slide in a direction parallel to the axis of the setting wheels 8. The method of guiding plate 15 upon platform 14 is not important but the present construction employs screws 16 secured to 35 said plate and adapted to travel within slots 17 formed in platform 14. On plate 15 are mounted two spur pinions 18 and 19 which are laterally offset from each other to such an extent that the space between them is a 40 trifle greater than the thickness of a setting wheel. These pinions are adapted to mesh with said setting wheels and the parts are so related that when the plate 15 is in one shifted position the pinion 18 will mesh with the setting wheel, and when said plate is in another 45 shifted position the pinion 19 will mesh with said wheel and when said plate is in intermediate position neither of said pinions will mesh with said setting wheel. Pinion 18 is 50 driven by gear wheel 6 and so also is pinion 19, but the latter indirectly through the agency of an idle gear wheel 20. The wheels 18, 19 and 20 consequently constitute a reversing gear, the idea being that when a setting wheel is being driven by pinion 18 it 55 will rotate in one direction and when driven by pinion 19 will rotate in the opposite direction notwithstanding the fact that the gear wheel 6 rotates always in the same direction. 60 Whether the totalizer adds, subtracts or does

not operate depends therefore upon the position of plate 15. I will now describe the controlling mechanism whereby plate 15 is automatically shifted.

65 *Controlling mechanism.*—At the rear edge 70 of plate 15 is a toothed rack 21 which remains permanently in mesh with the toothed segment 22^a formed upon the shifter 22. Said shifter is pivoted upon a pin 23 fixed in platform 14 so as to permit segment 22^a to 75 swing in a horizontal plane and thereby shift the plate 15. The means for rotating shifter 22 about its pivot are analogous to the corresponding parts shown and described in the aforesaid patent applications, and comprise 80 controlling pins 24 and cams 25. The pins 24, best shown in Fig. 2 and Figs. 4 to 8, are eccentrically set upon rectangular bases 26 adapted to be set in the rectangular pockets 27 in shifter 22 in any one of three positions 85 so that said pins may occupy a position toward the rear or toward the front or midway between. A controlling cam 25 is formed upon the bottom of each totalizer casting 30 and adapted to engage its respective 90 pin 24 as the totalizer travels past. As the cam travels in a fixed path it will cause the shifter 22 to swing about its axis and the effect produced upon the shifter will depend upon what position the pin occupies in its 95 pocket. In operation, if the operator sets the pin in such a position that it will lie toward the rear of its pocket, the plate 15 will be caused to assume one shifted position, but if he sets the pin so it will lie toward the 100 front of its pocket said plate will be caused to assume another shifted position, while if he sets the pin in an intermediate position the plate 15 will be caused to assume an intermediate position. Thus by setting the 105 pin in the proper position in its pocket the operator may before he commences to actually operate the machine, adjust it so that the controlling device will at the proper time cause the machine to add or to subtract or 110 not to operate the totalizer.

115 As it is desirable when a plurality of totalizers are employed to have each totalizer governed independently, the shifter 22 is provided with a row of pockets as shown in Fig. 2, and the cam 25 is so located upon the bottom of the totalizer that it will engage only its own respective pin. In consequence, each totalizer may have a different effect upon the shifter and the effect which one totalizer produces will be independent of the effect which a prior or succeeding totalizer produces.

120 *The totalizer.*—For the purpose of illustrating the invention, I will now briefly describe a suitable form of totalizer the parts whereof are shown in detail in Figs. 10 to 17 inclusive. As above mentioned they have been previously described in Patent No. 782,605.

The totalizer shaft 29 is non rotatably supported in the totalizer casing 30. Upon this shaft are supported a plurality of sets or groups consisting of five principal parts, to wit: the totalizing wheels 31, the carrying pinions 32, the receiving or accumulating wheels 33, the epicyclic pinions 34 and the intermediate wheels 35. Wheels 31, 33 and 35 are all freely rotatable about shaft 29 with the exception of wheel 35^a located at the extreme right to correspond with the units column. This wheel is rigid on the shaft and its function is to form a fixed basis or foundation from which the rotatable parts of the totalizer move their definite amounts.

In each group of parts 36 represents a disk like supporting piece which is splined to the shaft and has at its left portion a cylindrical hub 36^a which forms a bearing whereon the intermediate wheel 35 is freely rotatable. The pin 37 extends toward the left from piece 36 and serves as an axle whereon the carrying pinion 32 is freely rotatable. Said carrying pinion has four long and four short teeth which alternate with each other as best shown in Fig. 11. By means of the long teeth said carrying pinion is alternately locked and rotated by the locking ring 31^a and carrying teeth 31^b respectively of the totalizing wheel 31 at its right. The short teeth serve to make the left portion of the carrying pinion a complete eight toothed gear, and this left portion of the carrying pinion remains permanently in gear action with the internal gear portion 31^c of the next totalizing wheel to the left, by means of the gears 33, 34 and 35 hereinafter described. As the result the carrying action of pinion 32 is always transmitted to the next higher totalizing wheel 31. Each totalizing wheel 31 has a set of numerical figures on its exterior cylindrical surface and is supported by the contact of its internal cylindrical surface 31^a (which constitutes the aforesaid locking ring) upon the cylindrical edge of the supporting disk 36, said wheels 31 bearing loosely upon their supporting disks so as to be freely rotatable independently thereof.

The accumulating wheels 33 are plain spur gears having a comparatively large central aperture so that they may set over and be freely rotatable upon the points of the teeth of the intermediate wheels 35. Said accumulating wheels are narrow and their teeth project beyond the circumference of totalizing wheels 31, so that they may be engaged by the master wheels 13. The totalizing wheel 31^a and supporting piece 36^a (shown at the extreme left of Fig. 11) are slightly modified to impart a finished appearance to the extreme left end of the totalizer.

Extending leftward from each accumulating wheel 33 are two pins 33^a which constitute axles whereon the epicyclic pinions 34 are freely rotatable. Said epicyclic pinions

remain in mesh with both the intermediate wheel 35 and the internal gear portion 31^c of wheel 31 for transmitting rotation from one to the other. The aforesaid intermediate wheels 35 are wide faced spur pinions designed to both support the accumulating wheels 33 and also remain in mesh with the carrying pinions 31 and epicyclic pinions 34 at the left, and serve to transmit the carrying action of the carrying wheel to the epicyclic pinion and thence to the next higher totalizing wheel 31. As a result of the above described construction of the totalizer it follows that the accumulating wheels 33 are rotatable in either direction and when rotated in one direction will add and when rotated in the opposite direction will subtract.

In the general operation of the machine the operator sets a pin 24 in such position in its shifter 22 that it will when engaged by the cam 25 swing the shifter 22 about its pin 23 and thereby shift the plate 15 to such position as to bring either the pinion 18 or the pinion 19 or neither of them into line with the associated setting wheel 8 when the totalizer is opposite to such setting wheel. The depression of any figure key will therefore produce either addition or subtraction at that setting wheel or no motion.

Inasmuch as each totalizer has its cam 25 in a different relative position on the bottom of the totalizer casing any given totalizer will operate upon the pins in only one of the pockets of the shifter and hence different totalizers by preadjustment may be made to produce different kinds of effects upon this shifter; in other words by properly adjusting the controlling pins, the different totalizers as they pass a given setting wheel may be made to produce different results; for example one may produce addition, another subtraction.

With a plurality of setting wheels present as shown, a great variety of bills and accounts may be computed.

Attention is called to my copending application for patent for calculating machines, filed May 28, 1904, Serial No. 210,158.

What I claim as new and desire to secure by Letters Patent, is:

1. In a calculating machine the combination of a traveling totalizer; differential mechanism; means for transmitting the motion of the differential mechanism to the totalizer, said transmitting means being laterally shiftable parallel to the path of the totalizer and adapted to produce addition when in one shifted position and subtraction when in another shifted position; and controlling means operated by said totalizer for shifting said transmitting means to its different positions, a part of said controlling means being preadjustable to afford the operator a choice between addition and subtraction.

2. In a calculating machine the combination

tion of a traveling totalizer; differential mechanism; means for transmitting the motion of the differential mechanism to the totalizer, said transmitting means being laterally shiftable parallel to the path of the totalizer and adapted to produce addition when in one shifted position and subtraction when in another shifted position; and controlling means for shifting said transmitting means to its different positions, said controlling means including two coöperating members, one non traveling and the other traveling in unison with the totalizer, and one of said two members being adjustable for the purpose described.

3. In a calculating machine the combination of a traveling totalizer; differential mechanism; means for transmitting the motion of the differential mechanism to the totalizer, said transmitting means being laterally shiftable parallel to the path of the totalizer and adapted to produce addition when in one shifted position and subtraction when in another shifted position; and controlling means for shifting said transmitting means to its different positions, said controlling means including a cam and a pin, one of which is adjustable, said cam and pin being adapted to coöperate during a portion of the travel of the totalizer to automatically shift said transmitting means.

4. In a calculating machine the combination of a traveling totalizer; differential mechanism; means for transmitting the motion of the differential mechanism to the totalizer, said transmitting means being laterally shiftable parallel to the path of the totalizer and adapted to produce addition when in one shifted position and subtraction when in another shifted position; and controlling means for shifting said transmitting means to its different positions, said controlling means including two coöperating pieces, one a cam traveling with the totalizer and the other a non traveling adjustable pin.

5. In a calculating machine the combination of a traveling denomination carriage; a reversible totalizer; differential mechanism; laterally shiftable transmitting and reversing mechanism for transmitting motion from the differential mechanism to the totalizer in different directions depending upon the lateral position to which it is shifted; said transmitting and reversing mechanism shifting parallel to the path of the carriage and controlling mechanism for automatically shifting said transmitting and reversing mechanism, one portion of said controlling mechanism traveling in unison with the denomination carriage.

6. In a calculating machine the combination of a reversible totalizer; differential mechanism operating always in the same direction; axially shiftable gearing for transmitting motion from the differential mechan-

ism to the totalizer, said gearing comprising two trains of wheels one train being adapted to transmit motion to the totalizer in the same direction as that of the differential mechanism and the other train being adapted to transmit motion to the totalizer in the opposite direction to that of the differential mechanism; and controlling means for shifting said gearing axially to thereby throw into action one or the other of said trains of gears.

7. In a calculating machine the combination of a reversible totalizer; differential mechanism operating always in the same direction; axially shiftable gearing for transmitting motion from the differential mechanism to the totalizer said gearing comprising two trains of wheels one train having an odd number and the other an even number to thereby constitute a reversing mechanism; and controlling means for shifting said gearing axially to thereby throw into action one or the other of said trains of gears.

8. In a calculating machine the combination of a reversible traveling totalizer; differential mechanism; transmitting and reversing mechanism for transmitting motion from the differential mechanism to the totalizer, said transmitting mechanism being shiftable parallel to the path of the totalizer and including two trains of gear wheels one having an odd number and the other an even number of gear wheels to thereby constitute a reversing device; and means operated by the totalizer for automatically shifting the transmitting mechanism to thereby control whether the number of gear wheels actively interposed between the differential mechanism and the totalizer shall be odd or even.

9. In a calculating machine the combination of a traveling denomination carriage; a totalizer; differential mechanism; two sets of axially shiftable gear wheels for transmitting motion from the differential mechanism to the totalizer, one of said sets having an odd number of gear wheels and the other set an even number; and preadjustable controlling means operated by the totalizer for shifting one or the other of said sets of transmitting gear wheels into active position one portion of said controlling means traveling in unison with the carriage.

10. In a calculating machine the combination of a traveling denomination carriage; a reversible totalizer; differential mechanism operating always in the same direction; two sets of gear wheels for transmitting motion from the differential mechanism to the totalizer in the same ordinal places thereof one of said sets having an odd number of gear wheels and the other set an even number of gear wheels and both of said sets being axially shiftable into and out of active position; and preadjustable controlling means operated by the totalizer to shift said sets of transmission gear wheels to bring one or the

other of said sets into acting position to thereby enable the operator to predetermine whether the machine shall add or subtract.

11. In combination, a non traveling setting member, a reversible totalizer adapted to travel past it to be operated thereby; a differential mechanism; a non traveling transmitting and reversing mechanism adapted to shift parallel to the path of the totalizer and to transmit motion in different directions from the differential mechanism to said setting member depending upon the lateral position of said transmitting and reversing mechanism; and means for automatically shifting said transmitting and reversing mechanism.

12. In combination, a laterally fixed setting wheel; a reversible totalizer adapted to travel past it to be operated thereby; a differential mechanism; a transmitting and reversing mechanism for transmitting motion in different directions from the differential mechanism to the totalizer, said transmitting mechanism being adapted to shift laterally parallel to the path of the totalizer and adapted to produce addition or subtraction depending upon its position laterally; and controlling means operated by the totalizer for shifting said transmitting mechanism to the different lateral positions thereof, said controlling means being adapted to be set to different positions beforehand, whereby the operator is given a choice before commencing to operate the machine whether the number shall be added or subtracted.

13. In combination, a laterally fixed setting wheel; a plurality of reversible totalizers adapted to travel past it to be operated thereby; a differential mechanism; a transmitting and reversing mechanism for transmitting motion in different directions from the differential mechanism to the totalizers, said transmitting mechanism being adapted to shift laterally parallel to the path of the totalizer for producing addition or subtraction depending upon its position laterally; and controlling means independently operated by each totalizer for shifting said transmitting mechanism to the different lateral positions thereof, said controlling means having a plurality of independently adjustable members adapted to be operated by each totalizer individually for shifting said transmitting mechanism to the different lateral positions thereof.

14. In combination, a plurality of laterally fixed setting wheels, a reversible totalizer adapted to travel past them to be operated thereby; a differential mechanism; a plurality of independent non-traveling transmitting and reversing mechanisms, one associated with each setting wheel, for transmitting motion in different directions from the differential mechanism to the totalizer, each one of said transmitting mechanisms being

adapted to shift laterally parallel to the path of the totalizer to produce addition or subtraction depending upon its position laterally; and controlling means operated by the totalizer for shifting said transmitting mechanisms to the different lateral positions thereof, said controlling means being adapted to be set manually to either of two different positions before the commencement of the operation of the machine, for the purpose described.

15. In combination, a laterally fixed setting wheel; a reversible totalizer adapted to travel past it to be operated thereby; a differential mechanism; a non-traveling transmitting and reversing mechanism for transmitting motion in different directions from the differential mechanism to the totalizer, said transmitting mechanism being adapted to occupy any one of three different positions parallel to the path of the totalizer to produce either addition or subtraction or neither, depending upon its position laterally; and controlling means operated by the totalizer, said controlling means being adapted to be set manually to three different positions beforehand, for shifting said transmitting mechanism to said three different lateral positions, whereby the operator is given a choice before commencing to operate the machine whether the number shall be added or subtracted or not transmitted.

16. In combination, a laterally fixed setting wheel; a plurality of reversible totalizers adapted to travel past it to be operated thereby; a differential mechanism; a non traveling transmitting and reversing mechanism for transmitting motion in different directions from the differential mechanism to the totalizers, said transmitting mechanism being adapted to produce addition or subtraction depending upon its position laterally; and controlling means independently operated by each totalizer for shifting said transmitting mechanism to the different lateral positions thereof.

17. In combination, a laterally fixed setting wheel; a plurality of reversible totalizers adapted to travel past it to be operated thereby; a differential mechanism; a non-traveling transmitting and reversing mechanism for transmitting motion in different directions from the differential mechanism to the totalizers, said transmitting mechanism being laterally shiftable parallel to the path of the totalizers and adapted to produce addition or subtraction depending upon its position laterally; means for shifting said transmitting and reversing mechanism to its different positions, pins adjustably mounted in a part of said shifting means, and a cam on each totalizer for co-operating with one of said pins to operate said shifting means.

18. In a calculating machine, the combination of a traveling totalizer, differential

mechanism, means for transmitting the motion of the differential mechanism to the totalizer, said transmitting means being laterally shiftable parallel to the travel of the 5 totalizer and adapted to produce addition when in one shifted position and subtraction when in another shifted position and to not operate when in an intermediate position, and controlling means operated by said 10 totalizer for shifting said transmitting means to its different positions, a part of said controlling means being preadjustable to afford the operator a choice between addition, subtraction and non operation.

15 19. In a calculating machine, the combination of a reversible totalizer, differential mechanism operating always in the same direction, axially shiftable gearing for transmitting motion from the differential mechan-

ism to the totalizer, said gearing comprising 20 two trains of wheels one train being adapted to transmit motion to the totalizer in the same direction as that of the differential mechanism and the other train being adapted to transmit motion to the totalizer in the 25 opposite direction to that of the differential mechanism and controlling means for shifting said totalizer axially to thereby throw into action one or the other of said trains of gears or to throw both trains out of action. 30

In witness whereof, I have hereunto subscribed my name in the presence of two witnesses.
